UNITED STATES PATENT OFFICE

ALBERT NAU-TOURON, OF LE VESINET, FRANCE

RING TYPE SPINNING MACHINE

Application filed January 23, 1928, Serial No. 248,847, and in France January 22, 1927.

My invention relates to spinning or twisting machines and one of the improvements consists in providing a machine of this character with rings and slides, the rings being mounted on the usual spindle shifting plate and the slides being adapted to move freely around the periphery of the rings. One of the objects of my invention is to provide a device for braking the rings variably and at will in such wise that the slides have imparted thereto a relative variable displacement with respect to the rings thereof and at will depending upon the braking of the rings.

I thus maintain the tension of the thread constant in spite of the variation in winding diameter on the bobbin.

Other objects of the invention will be obvious to those skilled in the art to which my invention relates in the following description taken in connection with the accompanying drawing forming part of this specification, and in which:

Fig. 1 is a longitudinal section through my device with parts shown in elevation; and

Fig. 2 is a simplified plan view of Fig. 1 showing the braking arrangement.

Referring to the drawing, the device according to the invention comprises a ring 1 of any suitable material and in particular steel, treated in the usual manner. The shape of ring 1 may take any suitable form with respect to the longitudinal and transverse cross-section thereof, the form preferred being that shown in Figs. 1 and 2, it being well understood that the weight and the shape thereof are judiciously established in accordance with the function which it is to perform. The said ring is rotatably mounted on the usual spindle shifting plate 2 of the spinning machine from which it is inseparable in the vertical direction, its rotation taking place about the axis $x-x$ of the spindle with the interposition of a ball or analogous bearing 3, such as, for example, two rollers judiciously disposed.

It is to be noticed that the rolling friction between the ring and the member which supports it must be as small as possible, in

No. 248,847, and in France January 22, 1927.

order to tend toward greater facility of driving the ring 1 by a slide 5 thereon hereinafter referred to. The ring 1 terminates at its upper part in an annular flange 4, as is usual in the art and particularly in continuous spinning machines of the ring type, the shape of said flange is varied in accordance with the needs of the particular case under consideration and has working surfaces made up to obtain a suitable coefficient of sliding friction in accordance with the object in view.

The slide 5 is given a shape to suit that of flange 4 of the ring 1 over which it fits, the preferred form of the said flange being as shown in Fig. 1, that of a mushroom-shaped bead with respect to the section thereof, and is adapted to be freely displaced, as in the present continuous operating machines, with respect to the ring 1 by sliding on the said mushroom shaped bead upon which it is very loosely mounted.

The braking on the ring is preferably obtained by means of a drag cord 6 carrying a weight 6' at one end and fixed at the other end to the rear edge of the spindle shifting plate 2. The contact angle of cord 6 with the exterior peripheral surface of the ring 1 can be varied by displacing the free extremity thereof provided with the weight 6', either manually or automatically by suitable means. Such a disposition allows at all times to produce variable braking effects on the ring 1 and consequently variable speeds of rotation.

The ring 1 is concentrically disposed with respect to a spindle 7, of any type, and which might be provided with a tube or bobbin but is preferably a naked spindle as shown. In any case the spindle 7 is rigid with the thread which is wound upon it or with the bobbin thereof and turns about the axis $x-x$ which is made to exactly coincide with that of the ring 1.

The desirable features of my invention reside in the results obtained from a thread manufacturing point of view and its operation will now be described in detail.

When the machine is set in motion, and spindle starts to turn with increasing angu-

lar speed until its full constant speed is attained. At the same time, and under the effect of the tension of the thread tangent to the bobbin and due to the winding thereof on the bobbin, the speed of slide 5 increases parallel with that of spindle 7. The centrifugal force and the tension of the thread which act on the slide 5 increase also and in accordance with the square law of the speed of the slide 5 on the ring 1 in the same manner and so that the slide is progressively rotated around the ring. It follows that the relative displacement of the slide 5 on the ring 1 decreases as fast as the speed of spindle 7 increases. This displacement tends therefore toward a limit represented by the annulling of such relative displacement of the slide with respect to the ring. Said limit corresponds therefore to a fixed position of the slide 5 on the ring 1 and at an angular speed of the slide equal to that of the ring, the latter being as is known, equal to the angular speed known as the winding speed variable with the varying winding diameter of the thread on the bobbin.

With such an arrangement, if the ring were not braked, the thread being manufactured would be subjected to constantly varying tension since it would depend upon the varying winding diameter which gives way to a winding angle composed of varying forces, according to a known principle which has been proven experimentally.

In machine of this type known in the art and provided with a fixed ring having a slide the faulty operation is well known as there is no compensating effect and regulator for establishing equilibrium with a view to obtaining a constant tension of the thread irrespective of the varying winding diameter of the bobbin.

In my improved arrangement this regulation is easily brought about as it is founded upon theory which has been thoroughly verified by experiment.

The said regulation is essentially due to the braking of the ring and such braking continually preserves a certain speed of rotation of the ring and never instigates the stopping of said ring which is obvious.

The regulation of the tension of the thread is based on the new principle that the tension of the thread being manufactured may be regulated by utilizing along the working parts of the rotating system a certain amount of variable compensating work as a regulator which is a function of the varying winding diameter of the bobbin, which effect is produced as much along the tangent strands of the thread as the free strands.

It will be evident that all relative displacement of the slide 5 on the ring 1 instigates a certain amount of frictional work of sliding character which is equal to the product of the centrifugal force and the tension

of the thread acting on the slide and the coefficient of sliding friction of the slide on the ring and the distance covered by the slide on the ring, that is, the relative linear displacement of the slide on the ring. Now for one revolution of the spindle 7 this relative displacement depends obviously on the difference between the angular speed of the slide 5 and the angular speed of the ring 1. The angular speed of slide, which is equal to the winding speed, is, as is known, less than the angular speed of the spindle, that is, by one turn and is a function of the winding diameter. The speed of the ring being maintained by braking less than that of the slide in order to instigate in the whole rotating system the compensating and regulating work hereinbefore pointed out.

There is therefore obtained in my system a tension of constant magnitude on the thread being manufactured by varying the intensity of the regulating and compensating work as before mentioned at will and in accordance with the winding diameter and in such wise that in general the ring 1 is braked to a greater extent for winding thread on the large winding diameter of the bobbin than on the small diameter, the compensating work being therefore higher for the said large diameter than for the small diameter.

The purpose of the slide 5 is therefore vastly different in my system than that which is utilized in machines having a fixed ring. Consequently with my system I am enabled to manufacture threads of very different numbers with the same slide.

In addition, the slide 5 may be varied in shape and dimensions and may be given several arms of divers shapes having contact surfaces of different extent and development which are active to a greater or less extent on the corresponding surfaces of displacement and the action of the ring 1.

My improved machine allows the production of regular and constant winding or twisting under adjustable tension irrespective of the variations in diameter of the successive layers of wound thread and irrespective of the outline possessed by the wound thread.

Due to the constant tension, the thread is stronger and better wound and hence more thread may be wound on the bobbin. The number of breaks is diminished even with an increase in winding speed of the spindles. This results in a product of better quality and increased production over devices of the prior art.

In addition my system allows reduction of the minimum winding diameter usually employed and consequently reduction in the diameter of the spindle employed. This results in obtaining bobbins or cocoons of greater weight and therefore reduces the

number of times the thread has to be taken up during production.

Another important advantage, as previously mentioned, is the winding or twisting of a whole series of threads of different numbers or quality with the same slide.

While I have shown what I deem to be the preferable form of my device I do not wish to be limited thereto as there might be various 10 changes made in the details of construction and the arrangement of parts without departing from the spirit of the invention comprehended within the scope of the appended claim.

15 Having thus described my invention what I claim as new and desire to secure by Letters Patent is:

In a device of the type described having a rotatable thread spindle, a spindle shifting 20 plate concentric therewith, a ball race carried by said plate, a rotatable ring concentric to said spindle and said plate, a second ball race formed on said ring adjacent one end thereof, a plurality of balls disposed in said 25 ball races, a displaceable thread guide carried by the other extremity of said ring and means for increasing and decreasing the rolling between said plate and said ring at will for the purpose set forth.

30 In testimony whereof, I have signed my name to this specification at Paris, France, this 9th day of January, 1928.

ALBERT NAU-TOURON.
